US0D1039401S

(12) **United States Design Patent** (10) Patent No.: **US D1,039,401 S**
Li et al. (45) Date of Patent: ** Aug. 20, 2024

(54) **CONTROL DEVICE WITH NFC**

(71) Applicants: **Shenzhen Qiannyan Technology LTD**,
Shenzhen (CN); **Shenzhen Intellirocks
Tech. Co., Ltd.**, Shenzhen (CN)

(72) Inventors: **Mengxia Li**, Guangdong (CN);
Wenlong Wu, Guangdong (CN)

(**) Term: **15 Years**

(21) Appl. No.: **35/519,054**

(22) Filed: **Sep. 6, 2023**

(80) **Hague Agreement Data**

Int. Filing Date: **Sep. 6, 2023**

Int. Reg. No.: **DM/233031**

Int. Reg. Date: **Sep. 6, 2023**

Int. Reg. Pub. Date: **Nov. 17, 2023**

(51) **LOC (14) Cl.** 14-03

(52) **U.S. Cl.**

USPC **D14/218**; D13/168

(58) **Field of Classification Search**

USPC D10/49, 70; D13/162, 168; D14/218

CPC H04W 4/80; H05B 47/175; H05B 47/19

(57) **CLAIM**

The ornamental design for a control device with NFC, as shown and described.

DESCRIPTION

1. Control device with NFC

1.1 : Perspective

1.2 : Perspective

1.3 : Front

1.4 : Back

1.5 : Left

1.6 : Right

1.7 : Top

1.8 : Bottom
